APPARATUS FOR THE PRODUCTION OF
ELECTRICAL OSCILLATIONS

Albert Henry Midgley, Wembley, England

Application March 22, 1937, Serial No. 132,435
In Great Britain September 23, 1935

4 Claims. (Cl. 171—329)

This invention relates to apparatus for generating electrical oscillations or an undulating potential by electrostatic means more particularly for use in apparatus designed to produce by all electric means any musical notes or combinations of the same such as might be produced by an organ or like instrument.

The invention has particular reference to such apparatus of the kind employing a plurality of ring-shaped members of undulating or sine wave formation movable relatively to an electrode or electrodes in close proximity thereto, a difference of static potential being maintained between the members and the electrode or electrodes in order to generate an undulating potential electrostatically. One such form of apparatus is described in Patent No. 2,032,044, February 26, 1936.

In such apparatus each ring-shaped member and the electrode constitute the plates of a condenser, the capacity of which is varied in order to generate the undulating potential or electrical oscillations by the relative movement producing a variation in the effective plate area of the condenser, and the undulating potential or electrical oscillations are converted into sound waves by means of an amplifier and loud speaker.

In such apparatus as hitherto proposed the effective plate area is relatively small with the result that the working capacity is small and the impedances of the associated circuits must be of a high order and thus the leakage losses are great and the power generated is small.

The object of the present invention is to improve upon existing apparatus by obtaining a greatly increased capacity thus reducing the loss and increasing the power generated.

The invention consists in apparatus of the kind referred to for the production of electrical oscillations characterized in this that the, or each, electrode is also the sine wave or of undulating or zig-zag form.

Further features of the invention will be apparent from the description given hereafter.

The accompanying drawings illustrate several modes of carrying out the invention.

Figure 1 shows in elevation one-half of a convenient form of ring member and disc.

Figure 2 is a view showing two members of the form shown in Figure 1 displaced 180° out of phase relatively to one another.

Figures 3 and 4 are similar views to Figures 1 and 2 but showing a different form of ring member.

Figures 5 and 6 are again similar views showing a third form of ring member.

Figure 7 is an axial section of a structural form of the condenser including a diagram of the fundamental connections thereto for generating a partial note.

In carrying my invention into effect in one convenient manner I may proceed much in the manner described in Patent No. 2,032,044 by providing a stationary circular disc 10 of insulating material, to the face of which is fixed a number of concentric rings 11 of conducting material, the inner and outer edges of which may be of undulating or sine wave formation as shown in Figure 1.

There is provided one such ring for each semi-tone of the musical scale and the total number of rings provided will be dependent on the number of octaves of the musical scale which it is desired to reproduce, the number of undulations of successive rings progressing geometrically in the ratio of approximately

20

1 to $\sqrt[12]{2}$

which is the interval of a semi-tone.

Referring to Fig. 7 there is shown a second disc 10' of insulating material having concentric ring members 11' of conducting material of exactly the same number, construction and formation, as those of the first disc, which is adapted to be rotated by the shaft 14. The axis of each disc is in alignment and the disc 10' is mounted so that the radial surfaces of the sets of ring members on the respective discs are in close proximity and a difference of static potential is maintained between the members by any suitable means.

The apparatus may be completed by connecting the members to a keyboard and stop keys and in the manner as diagrammatically illustrated in Fig. 7 and described in the beforementioned specification. In other words, the secondary of the condenser is connected to a common amplifier which supplies a loud speaker 17 and when one of the undulating rings 11 in inductive relation to the secondary element is connected to a source of current an undulating potential will be electrostatically induced in the secondary element at a frequency depending on the speed of rotation of the shaft 14 and the distance separating the undulations of the ring 11. This undulating potential is applied to an amplifier 16 and a musical note will be emitted from the loud speaker 17 the pitch of which depends on the frequency and the intensity thereof depends on the potential to which the ring is subjected. The source of potential may be any suitable source and the con-

nection of the ring 11 to the source is made by the medium of a bus bar 18 which is adapted to be connected to a primary ring 11 by means of a contact 19 carried on a key 20 and adapted to be connected to the source by means of a contact 21 carried on a stop 22 of an organ. Each contact 19 is connected to a ring 11 through an adjustable resistance 23 and a resistor 24 so that each ring may be sufficiently charged from the source 10 by manual engagement of the organ keys 20.

Considering, for example, Figures 1 and 2, Figure 1 may be taken as showing two ring members exactly in phase while Figure 2 indicates the same two ring members displaced 180° out of 15 phase relatively to one another, and it will be seen that the effective condenser plate area is a maximum in Figure 1 and is a minimum in Figure 2, and the difference between the minimum and maximum condenser plate areas is relatively large 20 and therefore the working capacity and the power generated are both greatly increased as compared with known constructions so that the associated impedances may now be of a much lower order than those hitherto considered necessary 25 and thus the leakage losses will be considerably reduced.

Instead of making both the inner and outer edges of the ring member of sine wave or undulating formation the outer edge only may be so 30 formed as shown by the ring 11a in Figures 3 and 4 or, alternatively, the inner edge only may be of such formation. I may also shape the edges of the ring member in such a manner that each pair 35 of associated ring members may produce a tone containing more than one partial, one such form

of ring member 11b being shown in Figures 5 and 6.

Moreover in any modification of the invention each stationary ring member may be divided into sections of a circle insulated from one another 5 and the sections of each diametrically opposite pair may be connected together so that a different static potential may be maintained between the different sections and the corresponding rotating member as described in Patent No. 2,032,044. 10

Alternatively, the movable ring members may be so constructed in sections if associated with some suitable form of slip ring, commutator, or like construction to enable the necessary connections to be made. 15

I claim:

1. In an electrical musical instrument, an electrostatic generator adapted for the production of electrical oscillations comprising two relatively rotatable electrodes arranged in electrostatically 20 inductive relation, both of said electrodes consisting of rings of undulating form.

2. Apparatus according to claim 1 characterized by having each edge of both electrode rings of sine wave form. 25

3. Apparatus according to claim 1 characterized by the fact that the edges of each ring member are so shaped that a corresponding pair of ring members may produce a tone containing more than one partial. 30

4. Apparatus according to claim 1 characterized by the fact that the ring member constituting one electrode of the condenser and the associated electrode of the condenser are of identical sine wave form. 35

ALBERT HENRY MIDGLEY.
